Attest:

United States Patent Office.

HUGH TAGART, OF JACKSONTOWN, OHIO.

Letters Patent No. 77,677, dated May 5, 1868.

IMPROVED CATTLE-GUARD FOR RAILROADS.

The Schedule referred to in these Letters Patent and making part of the same.

TO ALL WHOM IT MAY CONCERN:

Be it known that I, HUGH TAGART, of Jacksontown, in the county of Licking, and in the State of Ohio, have invented certain new and useful Improvements in Railroad-Gates; and do hereby declare that the following is a full, clear, and exact description thereof, reference being had to the accompanying drawings, and the letters of reference marked thereon.

In the annexed drawings, making a part of this specification, A represents a circular hollow case or drum, cast in two parts, which forms a suitable case and bearings for the circular balance or weight B.

One of the parts of the case A is provided with lugs or ears, by which or through which it is screwed or bolted to the cross-ties of a railroad.

The balance or weight B is made of cast metal, substantially in the form shown, and is rigidly secured to a suitable shaft, H, which has its bearings in the case A. The weight B is made so as to exactly fit inside of its case and revolve therein, and its shaft H is made square at one end, so as to fit in a suitable socket therefor in the end of the adjustable shaft C.

The shaft C is made of suitable length to work between the two cases A A, and is provided with sockets in which fit the square ends of the shafts H H. Secured to the shaft C is a series of perpendicular rods or slats, D D, which extend across between the rails and form a gate or fence. The shafts H H may also have similar rods secured to them outside of the rails, if desired.

The cases A A, being closed as shown, keep the dirt or earth from the weight or balance B, so that there is no danger of its being clogged and prevented from operating and holding the shaft C in proper position.

Whenever a car or train of cars comes along either way, it will be seen that the rods D D may be readily pressed or turned down out of the way, and when the train has passed, the weights force them back to a vertical position, so that cattle or other stock are prevented from passing along the track.

For greater security, and to relieve the rods D D and shaft C from sudden jerks, I adjust a fall, F, to the cow-catcher of the engine, which is hung, as shown, at an inclination, so that the tops of the rods D are first struck, and thereby more readily turned out of the way.

The fall F is attached, in any suitable manner, to the engine or cow-catcher, and adjusted at any desired angle by means of a cord, g, as shown in the drawings.

Having thus fully described my invention, what I claim as new, and desire to secure by Letters Patent, is—

The combination of the case A, shaft H, and weight B with the shaft C, provided with a series of vertical rods, D D, when constructed substantially as described, and operated as and for the purpose specified.

In testimony that I claim the foregoing, I have hereunto set my hand, this 26th day of February, 1868.

HUGH TAGART.
